IRONING MACHINE

Nicholas L. Etten, Waterloo, Iowa

Application June 14, 1933, Serial No. 675,859

12 Claims. (Cl. 38—25)

This invention relates to domestic ironing machines and has for one of its objects the provision of hydraulic means for operating the mechanism thereof.

5 Another object is to provide a manually operated domestic ironing machine having hydraulic means for bringing about pressure between the ironing shoe and pad.

Still another object is to provide an ironing machine in which uniform pressure is automatically brought about between all portions of the surfaces of the pressing shoe and pad.

A further object is to provide an ironing machine mechanism adapted to automatically bring about uniform pressure between the ironing shoe and pad, which pressure is adjustable to permit an operator to apply light or heavy pressure upon materials being ironed to insure proper pressing thereof.

20 Other objects will appear in the following description and accompanying drawings in which—

Fig. 1 is an end elevational view of the complete machine showing in dotted outline certain of the parts in inoperative position;

25 Fig. 2 is a front elevational view of the same;

Fig. 3 is an outline plan view of a portion of the hydraulic system to be described, taken from line 3—3 in Fig. 2;

30 Fig. 4 is an enlarged sectional elevational view of the pump mechanism to be described, taken from line 4—4 in Fig. 2;

Fig. 5 is a plan view of pump lever parts to be referred to;

35 Fig. 6 is an enlarged sectional detail view of a portion of the pump mechanism to be described, taken from line 6—6, in Fig. 4;

Fig. 7 is a detail perspective view of a valve member to be described; and

40 Fig. 8 is a fragmentary sectional view showing details of a hydraulic cylinder to be described, taken on the line 8—8 in Fig. 3.

Referring to the drawings, Fig. 1 discloses the ironing machine as comprising a frame 10 supported upon legs 11 which are adapted to be secured to any suitable support such as a table 12.

45 Frame 10 is of skeleton construction having suitable extension portions for supporting the several elements of the mechanism including an upright extension portion 13 disposed on each end of the machine as indicated in Fig. 2.

50 Pivotedly supported at 15, on extensions 13, are lever members 16. A pressing shoe 17 is pivotally supported at 18 upon the outer ends of levers 16 and a hand rail 19, disposed parallel with shoe 17 and adapted to rest somewhat forward

thereof, is pivotally supported upon the levers at 20 by means of arm members 21.

Pivotedly attached at 22 to each of rearwardly extending portions 23 of levers 16 are toggle link assemblies comprising upper links 24 pivotally connected at 25 to lower links 26 which are pivotally attached at 27 to suitably disposed extending portions of frame 10.

Integral with the upper end of links 24 are lip extensions 27'. These extensions have notches 28 formed therein which are adapted to be engaged by rearwardly extending finger portions 29 of arms 21.

Lugs 30 projecting laterally inwardly from the body of levers 16 are so disposed as to limit pivotal movement of arms 21 through engagement therewith by fingers 29.

Considering the foregoing, it will be apparent that with the described parts in the position shown in solid lines in Fig. 1, toggle links 24 and 26 will rest in dead center relation with the lower portion of links 24 resting against extensions 31 of frame portions 13, in which position they are normally retained by means of fingers 29 resting against the upper sides of notches 28. Obviously the weight of hand rail 19 and arms 21 provides sufficient upward pressure, through the comparatively short lever arm 29, for the purpose.

With parts in the position noted, a slight manual upward movement of hand rail 19 will result in downward movement of finger 29 against the lower surface of notch 28 in extension 27', which movement is effective to rotate link 24 counterclockwise about the center 22 to break the dead center arrangement noted, whereupon further upward and backward movement of hand rail 19 will bring fingers 29 into engagement with lugs 30 to bring about unitary movement of levers 16 about the center 15. Continued movement as described will place the parts in the positions shown in dotted lines.

Thus is provided a simple, sturdy mechanism by means of which the pressing pad 17 may be lowered to a forward horizontal position, rigidly supported thereat against the buck, or conveniently removed to an upright position, as shown.

Referring to Figs. 1 and 2, it will be noted that pressing head 17 has its under surface longitudinally concaved the same being adapted to register with a complementally formed upper surface of an ironing pad 32 supported upon a frame or base member 33 when the head 17 is lowered on the buck. As viewed in Fig. 2, base 33 has its upper and lower portions joined by an offset neck

portion so that an overhung portion is provided which is adapted to conveniently receive tubular garments.

Extending downwardly from both ends of base 5 33 are pistons 34 which are slidably supported in forwardly extending portions 35 of frame 10 and pass therethrough into cylinder members 36 which are secured to the under side of the frame extensions. Compression springs 37, retained on pistons 34, act to cushion the base in 10 its lowered position.

Fig. 8 illustrates that cylinders 36 contain slide- 15 able floating head members 38 upon the lower sides of which are pliable sealing members 39. In the bottom of the cylinders are disposed support members 40 which act to support the head members above inlet orifices 41, formed in the lower side walls of the cylinders.

Fig. 3 illustrates that cylinders 36 are connected by a pipe line 42 and that they also communicate by pipe lines 43 and 44 with separate portions of a pump mechanism as will now be described.

Referring to Figs. 1, 2 and 4, the pump mechanism includes dual cylinders 46 and 47 integrally formed with a body 45. Body 45 is secured to frame 10 as indicated, the upper portion of the body being so formed as to provide a reservoir 48 for a purpose to be explained later.

Fig. 6 shows in detail the structure of cylinders 46 and 47 and associated mechanism which includes slideable piston heads 49 having central ducts 49', resilient packing disks 50 also having central ducts and recessed disk members 51 having central ducts, together with radially disposed ducts 51', the two latter disks being secured to the lower sides of the heads 49.

Coil springs 52 disposed within the cylinders and resting upon the bottoms thereof tend to 40 urge heads 49 toward the tops of the cylinders. In the bottoms of the cylinders are disposed screwed plugs 52' having central ducts 53. Plugs 52' are supported in cylinder end plugs 54 having central orifices 54' and countersunk portions 45 54''. The plugs are screwed into the ends of the cylinder tubes. Attachment plugs 55 having central ducts 56 are screwed into the bottom of plugs 54 and provide means whereby the terminals 57 of conductor tube 43, noted in Fig. 3, 50 are attached to the cylinders.

A check valve to prevent liquid from flowing into the cylinders from tube 43 is provided by a ball 58 disposed in recess 54'' and seated adjacent the lower opening of duct 53, the ball being normally held in contact with plug 52' by a spring 59.

Piston heads 49 are provided with check valves for preventing flow of liquid from the cylinders. The moving element of the valves is illustrated 60 in Fig. 7 as comprising a disk 60 having a corrugated under surface secured to a shaft 61 as shown, with a weighted portion 62 secured to its lower end.

As shown in Fig. 6, the valve element is disposed in the piston head in a circular recess formed in the upper face of disk member 51, with the shaft 61 loosely disposed in the central ducts of head 49, packing disk 50 and lower disk 51.

70 The recess of disk 51 is so dimensioned as to retain disk 60 in a loose manner with a small area of clearance around the disk and sufficient clearance between the under surface of disk 50 and the surface of the recessed portion of disk 75 51 to permit small vertical movement of the disk,

whereby when the piston head is moved downwardly, fluid contained in the cylinder is forced upwardly through the ducts 51' in disk 51 to quickly force disk 60 into contact with disk 50 to seal the duct thereof. It will be apparent that when liquid in the cylinder is not under pressure, disk 60 will normally rest with its corrugated surface in contact with the surface of disk 51, it being urged to this portion by gravity.

With disk 60 so placed, a passage will be formed between the exterior and interior of the cylinder by way of duct 49', the central duct of disk 50, through the open area above and around disk 60 through the corrugations on the under side thereof, through ducts 51' into the cylinder. The purpose of this valve arrangement will be made apparent shortly.

Figs. 4 and 5 will illustrate that piston heads 49 have, resting within recesses in their upper sides, vertical rods 63 and 64, the ends of the rods being rounded to permit angular movement of the rods in the recesses of the heads.

The upper end of rod 64 is pivotally secured by a pin 68 to a bifurcated lever 65 which is pivotally supported by means of a pin 67 upon a bracket member 66 extending from cylinder body 45.

The upper end of rod 63 is pivotally secured to a lower portion of a sub-lever 69, also pivotally supported by pin 67 and adapted to move thereon relative to the lever 65. Upward movement of the lever is limited by an extending portion 70 abutting the rear surface of bracket 66.

A U-shaped lever member 71 is pivotally mounted at 72 between the side members of lever 65. The upper end of this lever carries a pin 73 upon which is rotatably supported a collar member 74, the collar being retained between the side portions of the lever as shown.

The lever is urged to rotate clockwise upon the center 72 by springs 75, the opposite ends of which are hooked to the outer ends of pin 68. A notch 76 formed in the end of lever 69 is adapted to receive the collar 74, as urged by springs 75, to form a releasable coupling between levers 69 and 65, whereby lever 69 may move unitarily with lever 65 and rods 64 and 63 may likewise be unitarily moved. Obviously, due to a difference in distance from the center 67, the pressure, as brought about by pivotal movement of lever 65, would be relatively greater on rod 64 than upon rod 63.

Fig. 6 particularly illustrates the mechanism of cylinder 47 which is identical with that of cylinder 46 with the exception that adjacent its top in the wall of reservoir 48 is disposed a check valve mechanism comprising a body plug 77 having a central duct, a plug 78 secured therein having a central duct and recess 79 communicating with which is an orifice leading to a tube 44, already noted in Fig. 3.

A check ball 80 is urged by a spring 81 to close the duct of plug 78, an arrangement which would normally prevent liquid from flowing into reservoir 48. However, a pin 82 slidably disposed in the central ducts is adapted to hold the ball away from its seat when its opposite end is engaged by a lever 83 which is pivotally supported at 84 upon brackets formed in the wall of reservoir 48.

Rod 64 carries a collar 85 which is so disposed, when the rod is in elevated position as in Fig. 6, as to engage lever 83 and thereby propel pin 82 outwardly to open the check as noted.

Referring to Fig. 1, it will be noted that lever 65 terminates in a handle 65' which is located for-

wardly of the machine in a position convenient for operation by the user of the machine.

Having in mind the foregoing description, operation of the machine may now be explained 5 as follows:

It is assumed that the cylinder and piping system is filled with suitable liquid.

With the head 17 in lowered position and handle 65' in elevated position, a downward movement 10 of the handle will cause rods 63 and 64 to propel pistons 49 downwardly into cylinders 46 and 47 to force liquid therefrom through pipe lines 43 and 42 into cylinders 36 to propel piston heads 38 upwardly into contact with pistons 34 to 15 elevate the base 33 and thereby urge the pressing pad 32 into pressure relation with the head 17. Obviously, the manual pressure applied upon handle 65' will control the pressure exerted between pad 32 and head 17, the total pressure with- 20 in the system being an average of those developed within cylinders 46 and 47, the pistons of which are operated under different leverages.

It will be noted that during the down stroke of lever 65 piston 64 is moved downwardly to with- 25 draw collar 85 from contact with lever 63, whereby ball 80 is permitted to seat and thus prevent flow of liquid from the cylinder system into reservoir 18.

The mechanism for coupling levers 63 and 65 30 has already been noted. It will be clear that downward movement of lever 65 will result in building up pressure within the system, due to abutment of pad 32 by head 17, to a point where the pressure upon piston 49 of cylinder 46 is great 35 enough to overcome the resistance of roller 74 in notch 76, as produced by springs 75. At this point further movement of lever 65 will bring about escape of lever 63, with no backward movement thereof, due to the check in cylinder 46. Thus, piston 63 is rendered inoperative and the pressure load is placed upon piston 64, working 40 under comparatively high leverage, so that further downward movement of lever 65 will result in building up greatly increased pressure 45 which, as already noted, is uniformly exerted upon all parts of pad 32.

Upon return upward movement of lever 65, collar 85 is brought into engagement with lever 63 to unseat ball 80, as already noted, to allow liquid 50 to flow, as induced by the weight of base 33 operating upon pistons 34, backwardly into reservoir 48. In the meantime pistons 63 and 64 have been withdrawn from contact with heads 49 leaving them under the upward pressure influence of 55 springs 52, thus inducing a replacement flow of liquid from reservoir 48 around valve 60, as already described, into the cylinders.

When pistons 49 reach the top of their stroke, cylinders 46 and 47 will be properly filled with 60 liquid, ready for a subsequent cycle of operation. It has been noted that extension 70 of lever 63 prevents upward movement of the lever beyond a certain limit. Having this in mind, it will be apparent that continued upward movement of 65 lever 65 will eventually result in replacing collar 74 in notch 76 to reestablish coupling between the levers which will then also be ready for a new cycle of operation.

Practical operation of the machine would indicate the following procedure on the part of a 70 user.

With head 17 in upright position shown in dotted lines in Fig. 1, garments are placed on the pad 32, head 17 is brought down to horizontal 75 position adjacent the pad, handle 65' is moved

downwardly, operating both of cylinders 46 and 47, thus forcing a comparatively large volume of liquid into cylinders 36, to speedily elevate pad 32 into contact with the shoe and garments. Continued downward movement of the handle 5 will eventually break the lever coupling as described, whereupon the total manual pressure upon lever 65 is available at cylinder 47 as described, to bring about extremely high final pressure, at the will of the user, upon pad 32.

Although in Fig. 1 the head and the buck are shown as slightly separated after the handle 19 has been lowered, an initial pressure between these members is present during actual operation of the device when clothing is placed therebetween and even before the operating handle 65 has been actuated. This initial pressure is exerted because of the tension of the springs 37.

What I claim is:

1. An ironing machine having in combination a base, an ironing shoe and an ironing buck operatively mounted thereon, means for locking the shoe in operative position relative to the buck, hydraulic means for moving the buck relative to the shoe and manually operated pump means, said pump means for operating said hydraulic means comprising plural pumping cylinders unitarily operable, a manually operated member for actuating said cylinders unitarily, and means for member acts upon a less number of cylinders 20 inoperative whereby said manually operated member acts upon a less number of cylinders 25 to bring about increased pressure in said hydraulic buck moving means.

2. An ironing machine having in combination a base, an ironing shoe and an ironing buck operatively mounted thereon, means for locking the shoe in operative position relative to the buck, hydraulic means for moving the buck relatively to the shoe, manually operated dual pump means 40 for operating said hydraulic means, said dual pump means including a manually operated lever for operating the dual pump means upon partial movement to bring about comparatively rapid movement of said buck under relatively low pressure and upon further movement to bring about discontinuance of operation of a portion of the dual pump means, whereby the remaining portion thereof is rendered effective for applying relatively higher pressure to the buck moving means. 45

3. An ironing machine having in combination a base, an ironing shoe and an ironing buck operatively mounted thereon, means for locking the shoe in operative position relative to the buck, hydraulic means for moving the buck relatively to the shoe, manually operated dual pump means for operating said hydraulic means, said dual pump means including a manually operated lever means for actuating the dual pump means upon partial movement to bring about comparatively rapid movement of said buck under relatively low pressure and upon continued similar movement to bring about a condition of pressure which renders a portion of the dual pump means inoperative thereby rendering the remaining portion thereof operative, whereby further movement of said lever means brings about relatively high pressure between the shoe and buck. 60 65

4. An ironing machine having in combination a support, an ironing shoe and an ironing buck operatively mounted thereon, means for locking the shoe in operative position relative to the buck, hydraulic means for causing movement between shoe and buck to bring about pressure therebetween, means for actuating said hydraulic 70 75

- means including mechanism for changing its connection to the hydraulic means for facilitating the increase of pressure between shoe and buck during its actuation.
5. An ironing machine comprising a support, an ironing shoe, an ironing buck, means for locking the shoe in operative position relative to the buck, a manually operated lever, hydraulic means controlled by said lever to bring about a predetermined pressure between buck and shoe when said lever is moved partially through its complete path, and means altering the connections between the lever and the hydraulic means for facilitating the increase of pressure between shoe and buck when the lever is moved further.
6. A machine as set forth in claim 5, including means operable by movement of said lever to its initial position for automatically releasing said pressure.
20. 7. A machine as set forth in claim 5 in which said hydraulic means is provided with means so that the pressure brought about by operation of the lever will be maintained at any point even when the force applied to the lever is released.
25. 8. An ironing machine comprising an ironing shoe, an ironing buck mounted on a resilient yielding support, means for locking the shoe in operative position relative to the buck to apply an initial pressure between the shoe and buck, a manually operated lever, hydraulic means controlled by said lever to bring about a predetermined additional pressure between buck and shoe when said lever is moved partially through its completed path, and means altering the connection between the lever and the hydraulic means for facilitating the increase of pressure between shoe and buck when the lever is moved further.
30. 9. An ironing machine having in combination a support, an ironing shoe and an ironing buck operatively mounted thereon, means for locking the shoe in operative position relative to the buck, hydraulic means for bringing about pressure be-
- tween the shoe and buck, a manually operated lever for operating said hydraulic means, and means automatically operated when the resistance to the movement of the lever reaches a predetermined amount for altering the connections between the lever and the hydraulic means for facilitating the increase of pressure between the shoe and buck.
10. A portable press-type domestic ironing machine comprising a support, an ironing shoe and a buck supported thereby, means for locking the shoe against the buck, hydraulic means for bringing about pressure between the shoe and buck, manually operated lever mechanism pivotally mounted on the support for operating said hydraulic means, said manually operated lever mechanism including a hand grip situated in a position convenient to be actuated by the hand of an operator seated before the machine.
15. 11. In an ironing machine of the class described, a head movable toward and from ironing position, means for locking said head in ironing position, a movable buck, said buck capable of engaging said head in one of its positions, spring means normally supporting said buck, pressure creating means for forcing said buck toward said head to create an ironing pressure therebetween, and a variable length non-yielding transmission mechanism connecting said buck with said pressure creating means.
20. 12. In an ironing machine of the class described, the combination of a frame, a buck supported on said frame for vertical movement, a head adapted to be locked in rigid position above said buck, fluid motor means for raising said buck into engagement with said head, a fluid reservoir, a pump supplied therefrom, means for operating said pump to force fluid under pressure into said fluid motor means, and connections between said buck and said fluid motor means whereby the weight of said buck returns said fluid to said reservoir.
25. 30. 35. 40. 45.

NICHOLAS L. ETTER.
